UNITED STATES PATENT OFFICE.

FREDERICK SCHMITT, OF OAKLAND, CALIFORNIA.

BOILER-FLUE-SETTING DEVICE.

Application filed October 21, 1920. Serial No. 418,346.

To all whom it may concern:

Be it known that I, FREDERICK SCHMITT, a citizen of the United States, residing at Oakland, in the county of Alameda and State of California, have invented certain new and useful Improvements in Boiler-Flue-Setting Devices, of which the following is a specification.

This invention relates to improvements in boiler flue setting devices of that type disclosed in my previous Patent No. 1,222,806, granted April 17, 1917.

These improvements have been designed with the object primarily of eliminating the tendency of leakage which is sooner or later produced or occurs owing to the methods employed at the present time of setting tubes or flues in boilers, especially those subject to very high pressures, but in addition, I have had in view the production of a construction and arrangement of parts which, while very similar to those of my previous patent mentioned, yet give rise to greater facility in application or removal of the flues, greater insurance against leakage of the joints, and considerable economy in material without sacrifice of the required strength or resistance against fracture.

To best appreciate the advantages of my present construction it may be noted that at the present time the rolling method in the application of flues is employed, and a heavy flue sheet is required in order to obtain the necessary strength to withstand the strains of expansion and contraction of the tubes under actual working conditions. With my construction a much lighter sheet may be utilized since in the application of the tube the metal of the same is not weakened by any manipulation thereof as is required in the rolling processes. With the adoption of a lighter flue sheet a greater flexibility is secured, thus permitting the usual distortion which is occasioned by the expansion and contraction, but without the resulting tendency to fracture of the metal about the bridge walls of the sheet and about the flanged portions where riveted to the boiler fire box supports. This is of great importance, for I have found from practical experience extending over many years that boiler tubes can not be maintained tight for any definite period unless the flue sheet is permitted to travel with the tubes as expansion and contraction takes place. Many other difficulties resulting from the rolling

method of attaching tubes might be recited, and all of which are eliminated by my improvements. These will become apparent as this description proceeds and the invention becomes fully understood.

Referring now to the drawings for a full understanding of my present invention, reference is to be had to the following description and accompanying drawings in which:

Figure 1 is a vertical sectional view showing the specific flue fastening means of this invention;

Figure 2 is a sectional view of the bushing or thimble element;

Figure 3 is a similar view of the securing and clamping member; and

Figure 4 is a view similar to Fig. 1, but showing a modified form of the flue involving the enlarged extremity sometimes found desirable.

Throughout the following description and on the several figures of the drawing, similar parts are referred to by like reference characters.

In the drawings, A designates the flue sheet which is provided with the usual flue openings, any suitable number of which are employed depending upon the capacity or requirements of the boiler. B designates a flue which is connected thereto by the fastening means forming the particular subject matter of this invention and consisting of the bushing or thimble 1 and the securing or clamping member 2 shown in Figs. 2 and 3 respectively.

Referring to the bushing 1 it will be observed that at one end this is provided with an annular shoulder or head 3 while at its other end the bushing is formed with an inner annular shoulder 4 constituting a seat against which the end of the flue B abuts. Externally this bushing is threaded as indicated at 5 so as to be screwed into the threaded flue openings of the sheet A. In the application of the bushing the same is screwed into the proper opening until the annular shoulder engages with the outer face of the flue sheet. In other words this bushing, contrary to the operation of the equivalent element in my previous patent, is introduced into the opening from the outside and is screwed against the end of the flue or tube so as to firmly seat this end against the shoulder 4 thus constituting a joint the snug seat of which is controlled by the action of screwing home the bushing as above de-

scribed. The joint is made more firmly snug by manipulation of the clamping and securing member 2 which will now be described.

- 5 The member 2 is provided at one end with the annular head 6 and exteriorly threaded at its other end as indicated at 7 to a point substantially midway of this element so as to be screwed into the tube B which is correspondingly threaded for this purpose. Between the threaded portion 7 and the head 6 this member is formed with a tapering surface 8 which conforms to a similar formation of the interior of the thimble or bushing 1 as indicated at 9, so that a main or primary seat between these two parts is thereby provided. The inner periphery of the annular shoulder 3 of the bushing is reamed out so as to form a further seat 10 that conforms to the shape of the surface of the head 6 of the securing member 2 so that when the latter is screwed into place as shown in Fig. 1 of the drawing, a snug leak-proof joint is provided at this point. With this form of construction it is readily feasible in the reseating of tubes to renew or reseat the inner bearing surfaces of the bushing and securing member should it become necessary.

As will be apparent from the foregoing description in the application of my connecting means, since both elements thereof are introduced into the flue sheet openings from the outside of the sheet, the operation is greatly facilitated and it is possible to remove any one or number of tubes at any time it is necessary so to do without difficulty, thus permitting of maintaining the boiler clean and affording a means of access to such parts of the boiler structure for such purposes of inspection or other reasons as are now substantially inaccessible without cutting out the tubes. In other words, with this arrangement of the parts it is never necessary to cut out a tube when it is desired to remove the same, unlike the invention of my previous patent referred to or the constructions now generally in use which are connected to the flue sheet by the rolling processes hereinbefore mentioned. It will be apparent that one of the reasons which make it necessary to employ a relatively thick flue sheet resides in the fact that in use different tubes or flues expand to different extents so that as a result the flue sheet is unevenly distorted and when after use some of these flues are replaced a different length of tube from the original is required so that the flue sheet undergoes extreme stresses due to the differences in the lengths of the tubes which are employed. With this relatively heavy flue sheet the uneven stresses have a great tendency to fracture the metal owing to these uneven strains, but in the use of my invention above described, tubes of a predetermined length throughout are capable

of being used and the adjustment of the connection is employed to great advantage to secure the proper leak-proof joints that are necessary in high pressure boilers such as used on locomotives. Under the conditions it therefore becomes possible for a lighter flue sheet to be employed and this permits of greater flexibility and less tendency to fracture is the result, since the flue sheet will more readily follow the even expansion and contraction of the flues. Another great advantage of this arrangement of parts described hereinbefore lies in the fact that the expansion of the tubes in use tends to more snugly fit the joints which is of great importance as will be obvious to one skilled in this art.

In the manipulation or application of the clamping or securing member 2 the tube B is drawn against the shoulder 4 when this member is screwed home and this action together with the preliminary seating of the end of the tube against said shoulder produces a most excellent leak-proof joint at this point. The tapered construction of the bearing surfaces of the bushing and securing member also produces a leak-proof fitting of the parts as will be obvious. It will be understood that one of these connecting means may be used at each end of the tube or I may employ the device above described at one end and the form of the invention shown in my previous patent at the other end.

.. The only difference between the form shown in Figs. 1 and 4 lies in the enlargement of the end of the flue B' at the point indicated at 11, the advantages of the preferred construction being equally present in this arrangement so that they need not be further referred to.

Having thus described my invention what I claim as new and desire to secure by Letters Patent is:—

1. In combination, a flue sheet provided with a flue opening, a flue, a bushing adapted for insertion in said opening from the outer side of said flue sheet and extending slightly beyond the inner side of said flue sheet so as to form a supporting extension for the end of the flue seated therein, said flue terminating short of said flue sheet, and a clamping and securing member adapted for insertion from the corresponding side into the mouth of the flue.

2. In combination, a flue sheet having a flue opening, a flue, and means for connecting said flue to the sheet including a bushing adapted for insertion in said flue opening into abutting engagement with the end of the flue, said flue terminating short of the flue sheet, and a clamping member insertable through said bushing into engagement with the flue and operable to draw the flue into firm contact with the bushing.

3. In combination, a flue sheet having a flue opening, a flue arranged at one side of said sheet, and means for connecting said flue to the sheet including a bushing adapted for insertion into said opening from the side opposite the flue to abut and produce pressure against the end of the flue in a direction longitudinally thereof for seating purposes, and a clamping and securing member engageable with the interior of the mouth of the flue to draw the same in the opposite direction.
4. In combination, a flue sheet having a flue opening, a flue, a bushing having threaded connection in the flue opening and formed at one end with an annular shoulder adapted to seat against the outer face of the flue sheet and an inner annular seat at its opposite end to receive the flue, said bushing being capable of firmly seating the flue on said seat in the operation of screwing the bushing home, and a clamping and securing
- member exteriorly threaded at one end for connection with the flue and operable to draw the flue against the end seat of the bushing as aforesaid.
5. In combination, a flue sheet having threaded openings therein, flues, and fastening means for connecting the flues in the openings comprising a bushing exteriorly threaded and having a shoulder at one end and a flue seat at its opposite end, said bushing being provided with an interior contracted bearing surface, and a securing and clamping member formed intermediate its length with a bevelled bearing surface corresponding to the contracted surface of the bushing, said securing member being exteriorly threaded at one end to extend into the flue and headed at its other end to coact with the bushing when screwed home.

In testimony whereof I affix my signature.

FREDERICK SCHMITT.
